Primary Examiner — Cynthia M. Chin(74) *Attorney, Agent, or Firm* — Tillman Wright, PLLC; James D. Wright; David R. Higgins(57) **CLAIM**

The ornamental design for a self-propelled skateboard, as shown and described.

DESCRIPTION

FIG. 1 is a perspective view of a self-propelled skateboard, showing my new design;

FIG. 2 is a top view thereof;

FIG. 3 is a bottom view thereof;

FIG. 4 is a left-side elevation view thereof;

FIG. 5 is a right-side elevation view thereof;

FIG. 6 is an enlarged front elevation view thereof; and,

FIG. 7 is an enlarged rear elevation view thereof.

The broken lines are for the purpose of illustrating portions of the article that form no part of the claimed design.
